CLAIM

The ornamental design for a power sander as shown and described herein.

DESCRIPTION

FIG. 1 shows a top perspective view of a power sander, according to some embodiments of the present invention; FIG. 2 shows a front view of the power sander shown in FIG. 1; FIG. 3 shows a back view of the power sander shown in FIG. 1;

FIG. 4 shows a right side view of the power sander shown in FIG. 1;

FIG. 5 shows a left side view of the power sander shown in FIG. 1;

FIG. 6 shows a top view of the power sander shown in FIG. 1; and,

FIG. 7 shows a bottom view of the power sander shown in FIG. 1.

The broken lines depict portions of the power sander in which the design is embodied that are not considered part of the claimed design.

1 Claim, 7 Drawing Sheets
